LOUVERED UNIT

Robert H. Bishop, 808 W. Park St., Champaign, Ill.

Filed Nov. 7, 1963, Ser. No. 77,321

Term of patent 14 years

(Cl. D13—1)

FIG. 1

FIG. 3

FIG. 2

FIGURE 1 is a front, side elevational view of a louvered unit embodying my design, which view has a broken-away center portion so as to indicate the indeterminate width of the louvered unit;

FIGURE 2 is a rear, side elevational view of the louvered unit shown in FIGURE 1, which view has a broken-away center portion so as to indicate the indeterminate width of the louvered unit;

FIGURE 3 is an end elevational view of the FIGURE 1 louvered unit as viewed along the section line 3—3.

The dominant features of the design are shown in full lines. The center of the louvered unit in FIGURES 1 and 2 is broken away to indicate indeterminate length.

This is a continuation-in-part of application Serial No. D. 66,483, filed August 24, 1961, and now abandoned.

I claim:

The ornamental design for a louvered unit, substantially as shown and described.
